UNITED STATES PATENT OFFICE.

GEORGE E. FULTON, OF JERSEY CITY, NEW JERSEY.

COMBINATION TURBINE AND MUFFLER.

No. 838,018.

Specification of Letters Patent.

Patented Dec. 11, 1906.

Application filed March 9, 1906. Serial No. 305,039.

To all whom it may concern:

Be it known that I, GEORGE E. FULTON, a citizen of the United States, residing at Jersey City, in the county of Hudson and State 5 of New Jersey, have invented certain new and useful Improvements in Combination Turbine-Motors and Mufflers, of which the following is a specification, such as will enable those skilled in the art to which it appertains to make and use the same.

My invention relates to pressure-fluid engines, and particularly to an improvement in mufflers, which form a part thereof and which are applied to the exhaust-pipe of such pressure-fluid engines; and the object of my invention is to utilize a certain percentage of heat units contained in the exhaust-gases for motive purposes, a further object being to provide in combination herewith an efficient 15 muffler for the exhaust-gases of a pressure-fluid engine to which my invention is applied; and with these and other objects in view the invention consists in a combined turbine-motor and muffler of the class specified, constructed as hereinafter described and claimed.

The invention is fully disclosed in the following specification, of which the accompanying drawings form a part, in which the separate parts of my improvement are designated by suitable reference characters in each 20 of the views, and in which—

Figure 1 is a cross-section of my improved apparatus on the line 1 1 of Fig. 2 looking in the direction of the arrow *x*. Fig. 2 is a vertical section on the line 2 2 of Fig. 1. Fig. 3 represents a cross-section on the line 1 1 of Fig. 2 looking in the direction of the arrow *y*; Fig. 4, a partial section on the line 4 4 of Fig. 3, and Fig. 5 is a side view of a four-cylinder pressure-fluid engine with my combined turbine-motor and muffler attached to the exhaust-pipe of the same.

In my improved muffler I unite the muffling features with a turbine set in motion by 45 the combined action of steam and gas under pressure. The steam as a motive power is generated within the muffler, one portion of which serves as a flash-boiler supplied with water from a tank or pump under pressure. 50 The heat necessary to operate the flash-boiler is derived from a part of the exhaust-gases which pass through the muffler, and the steam thus generated is made to impinge against the blades of the well-known device, 55 a turbine-motor. This motor, running in bearings, forms a part of the muffling appa-

ratus, and the turbine itself is also placed within said muffler. Another part of the heat of the escaping exhaust from the main pressure-fluid engine is made use of to expand to a lower stage within the muffler and is then admitted to the blades of the turbine-motor to assist the steam heretofore mentioned and generated within the muffler to rotate the turbine-wheel by also impinging 60 against the blades of the same. After this combined motive power, which heretofore has been wasted by exhausting directly into the outer air, has given up a certain percentage of its heat units transferred into motive 65 power, the same is exhausted under nearly atmospheric pressure into the outer air.

As illustrated in Fig. 5 of the drawings, my combined motor and muffler *a* is attached to the exhaust-pipe *b* of the four-cylinder pressure-fluid engine *c*. The power generated within my apparatus, as shown in the drawings, is transmitted by means of a belt *d* and the pulley *d'*, attached to the shaft *d* of the turbine-motor, to the pulley *d*, attached 70 to a shaft *d* for the purpose of running a fan, which may be used in this instance for the purpose of air-cooling the jackets of the main cylinders of the engine *c*. It is obvious that the power thus generated by means of my 75 apparatus may, by means of proper transmission, be made use of to assist the main engines driving the main shaft of the same for running the dynamo of the electric sparking device, &c.

The apparatus proper consists of the following features, which consist of an outer circular side plate *e*, provided with a boss *e'*, which is provided with an internal screw-thread, to which can be attached the exhaust-pipe *b* of the main pressure-fluid engine. Another circular side plate *e*, corresponding in size, shape, and dimensions to the former side plate *e*, is also provided with an internal threaded boss *e*, to which an atmospheric escape-pipe can be attached. These two circular side plates *e* and *e* are bolted to an annular casing-ring, which is composed of two integral parts *f* and *f'*, the outer ring *f* having inwardly-extending corrugations *f*, while the inner ring *f'* has outwardly-extending corrugations *f*. These rings are placed concentrically with each other, leaving at their corrugated joint an air-space *f*, which extends circumferential, as well as transversely.

A number of circular partition-plates *g*, *h*, *i*, *k*, and *l* and circular washers *m*, *n*, and *o*,

all conforming in diameter with the outer casing-ring f and the side plates e and e^2 and having a corrugated open space corresponding to the air-space f^4 , above mentioned, are joined together with the above-named side plates e and e^2 and the casing-rings f and f' by means of the bolts p , which pass transversely through these plates and rings, as illustrated in Fig. 2 of the drawings, and when arranged in the manner indicated in said figure they form a closed circular muffling device, with two large compartments q and r and three small compartments s, s' , and s^2 .

The outer side plate e is also provided with an outwardly-extending boss e^4 , to which is attached a pipe e^5 , which is adapted to be connected with a tank or pump bringing water under pressure, if so desired, into the interior of the narrow air-spaces s within the muffling device, which air-spaces, as illustrated in the drawings, are contiguous to and interconnected with each other.

Placed within the larger chamber q is a worm of copper tubes q' of one or a number of series of convolutions. One terminal of this worm connects at q^2 with the steam-chamber s' , which latter is formed by the circular partition-plates i and k and the intervening washer n , while the other terminal of said worm q' connects with the same steam-chamber s' at q^3 .

By this means the interior of the copper worm q' , the chamber s' , the circumferential corrugated space f^4 , the chambers s' and o^2 , respectively, formed by the outer end plates e and e^2 and the partition-plates g and l , and washers m and o form one closed chamber, which is the flash-boiler proper, to which water can be admitted by means of the pipe e^5 and from which steam can be generated within the same, and said steam finds its exit by means of two steam-ports u and u' , located in the partition-plate k . The tubes q' are made, preferably, of copper or brass and are flattened, so as to present in their cross-sectional area a narrow water-heating steam-generating space, which, together with the narrow water and steam spaces f^4, o', o , and o^2 and when sufficiently heated will almost instantly convert the hereby admitted water into steam.

The exhaust-gases from the main pressure-fluid engine entering, as above described, the smaller hot-air chamber r will expand therein, give up a part of their heat to the adjoining partition-walls g and i , and thereby perform the functions of this part of the flash-boiler. A series of outlet-ports v , as shown in Fig. 3, are located in the partition-wall i , said outlet-ports v being placed, as are also the steam-ports u and u' , radially to the axis of the apparatus and connected with the larger hot-air chamber q , as shown in Fig. 4, and an individual washer v' , provided with a corresponding opening, being

placed within the steam-chamber s' in order to cut off the communication therewith and to permit of the exit of the gases from the chamber r direct into q . The gases after impinging against the radial blades of a turbine-motor w , located within the chamber q and more fully described hereinafter, will again expand and give up more of their heat to the outer walls of the adjoining flash-boiler and the copper tubes q and will then exhaust into the outer air under nearly atmospheric pressure, thereby serving the combined purposes of a sound-muffler to the main pressure-fluid engine to which my apparatus has been attached, as well as generating steam for secondary motive purposes and also serving direct as a motive power.

The turbine-motor shaft w' is mounted in ball-bearings w^2 , as shown in Fig. 2 of the drawings; but these bearings may be of the usual form of plain bearings, and they are bolted to the end plates e and e^2 and form, with the shaft w' , the axis of the motor or muffling device. A turbine-wheel w , having the usual radial blades w^3 , is placed between the two concentric band-supports w^4 and w^5 , the latter being supported by the central web member w^6 , which in turn is attached to the shaft w' by means of lock-nuts, set-screws, or keys.

The blades w^3 of the turbine-motor receive the impact of the steam issuing from the steam-ports u and u' , as well as from the gas-ports v , which will cause the same to be rotated in the manner of impact-engines.

It will thus be seen that by means of my combined motor and muffling device motive power is generated from the exhaust of any pressure-fluid engine to which the same may be attached and that my device also acts as a muffler by reducing the exhaust pressure fluid to a lower stage before expanding the same into the outer air.

Having fully described my invention, what I claim as new, and desire to secure by Letters Patent, is—

1. A combined turbine-motor and muffling device for pressure-fluid engines and operated by the exhaust from the same, having a flash-boiler for steam-generating purposes, and one or more chambers for the temporary reception of the exhaust, and a turbine-motor, substantially as shown and described.

2. A combined turbine-motor and muffling device for pressure-fluid engines operated by means of the exhaust fluid entering the same from the exhaust-pipe of said pressure-fluid engine, and having a turbine-motor set in motion by means of the combined action of steam generated within the device and by the direct impact of said exhaust fluid, substantially as shown and described.

3. A combined turbine-motor and muffling device operated by making use of the heat contained in the exhaust fluid of a pres-

sure-fluid engine to which this device has been attached, the heat of said exhaust being utilized to generate steam in a boiler contained within the device, such steam serving to generate motive power by its impact against the blades of a turbine-motor which also forms part of the device, substantially as shown and described.

4. In a turbine-motor and muffling device, 10 a casing containing a flash-boiler which can be provided with water for steam-generating purposes, a turbine-motor set into operation by means of the impact of steam obtained from the flash-boiler and also operated by 15 means of the impact of the entering exhaust fluid of any pressure-fluid engine to which said device is attached, said exhaust fluid entering said device serving also to impart its heat to the generation of steam in the afore- 20 said flash-boiler, substantially as shown and described.

5. In a turbine-motor and muffling device, 25 means for employing the impact force of the exhaust fluid taken from a pressure-fluid engine to which the same is attached combined with means for employing the impact force of steam generated by the heat of said exhaust fluid, such combined impact forces to be directed 30 against the blades of a turbine-motor which forms a part of the combined turbine-motor and muffling device, substantially as shown and described.

6. In a turbine-motor and muffling device, 35 means for employing the impact force of the exhaust fluid taken from a pressure-fluid engine to which the same is attached combined with means for employing the impact force of steam generated by the heat of said exhaust fluid, such combined impact forces to be directed 40 against the blades of a turbine-motor which forms a part of the combined turbine-motor and muffling device, the shaft of the

turbine-motor serving to transmit the power thus obtained for motive purposes, substantially as shown and described.

7. A turbine-motor and muffling device 45 containing means whereby the heat and pressure of the entering exhaust fluid of a pressure-fluid engine to which this apparatus has been attached becomes partly abstracted and 50 applied to a special motive-generating device forming part of this apparatus and means whereby the pressure of the entering exhaust fluid is reduced to a lower stage and expanded into the atmosphere at a greatly-reduced 55 pressure, substantially as shown and described.

8. A combination turbine-motor and muffler having a casing provided with a series of compartments, one compartment of which 60 serves in conjunction with a coil of tubes as a steam-generating boiler supplied with water and heated by the entering exhaust fluid of an attached pressure-fluid engine, and one or 65 more additional compartments for the reception of said entering exhaust fluid for the purpose of reducing its pressure and also to impart some of its heat to the walls of its adjoining compartments, a turbine-motor having a shaft and power-transmitting device 70 and mounted within the apparatus and receiving the direct impact of the exhaust fluid and the direct impact of the steam generated within the apparatus, substantially as shown and described.

In testimony that I claim the foregoing as my invention I have signed my name, in presence of the subscribing witnesses, this 7th day of March, 1906.
